(57) CLAIM

The ornamental design for a handheld hooked implement, as shown and described.

DESCRIPTION

FIG. 1 is a side view of a handheld hooked implement showing my new design, with the opposing side view being a mirror image;

FIG. 2 is a top view thereof;

FIG. 3 is a bottom view thereof;

FIG. 4 is a left end view thereof viewing the left end of the implement in FIG. 1; and,

FIG. 5 is a right end view thereof viewing the right end of the implement in FIG. 1.
